(57) **CLAIM**

The ornamental design for an elongated tube, as shown and described.

DESCRIPTION

FIG. 1 is an isometric view of our elongated tube;
 FIG. 2 is a left side view of the elongated tube in FIG. 1;
 FIG. 3 is a right side view of the elongated tube in FIG. 1;
 FIG. 4 is a front side view of the elongated tube in FIG. 1;
 FIG. 5 is a rear side view of the elongated tube in FIG. 1;
 FIG. 6 is a top plan view of the elongated tube in FIG. 1; and,
 FIG. 7 is a bottom plan view of the elongated tube in FIG. 1.
